AUTOMATIC SPARK ADVANCE FOR
MAGNETOS

Gerald J. Shaw, Lamar, Mo., assignor to Outboard Marine Corporation, Waukegan, Ill., a corporation of Delaware
Filed Sept. 1, 1960, Ser. No. 53,510
12 Claims. (Cl. 315—218)

This invention relates to an automatic spark advance for magnetos.

The invention is exemplified by conventional illustrations of parts of a flywheel magneto. Because maximum spark intensity is achieved if the primary circuit of the spark coil is opened when the coil is threaded by flux changing at maximum rate, it is routine to advance or retard the armature upon which the coil is wound coincidentally with the advance or retard of the breaker cam follower in order to maintain the desired relationship. However, the present invention takes advantage of the fact that in a flywheel magneto having a so-called E armature, separate peaks of rate of flux change are built up as the poles of the permanent magnet pass the several poles of the armature. The highest peak occurs, of course, when the direction of flux flow is reversing in the central leg upon which the coils are wound. However, there is a lesser peak which occurs as the poles of the flywheel magnet first come into registry with one of the side legs and the center leg of the armature, thus initiating flux rise through the coils.

By an arrangement such that the breaker cam is advanced with respect to the breaker cam follower for a distance approximately equal to the angular spacing between the points at which these two peaks occur, I have achieved a spark advance which does not involve any movement of the E armature or breaker plate, the cam alone being shifted through an angle such that the opening of the primary circuit is shifted from low speed synchronism with the maximum peak rate of flux change, to high speed synchronism with the lesser but adequate peak of flux buildup, thus giving an ignition spark intensity which is far above average at low speeds (for starting) and is entirely adequate for proper ignition at high speeds.

In the drawings:

FIG. 1 is a diagrammatic view showing the relation between the flywheel magnet and the armature at high engine speeds, the magneto shaft being shown in section approximately on the line 1—1 of FIG. 6.

FIG. 2 is a view showing the relationship between the breaker cam and cam follower at high speeds, when the flywheel and armature are in the relative positions of FIG. 1, FIG. 2 being taken approximately in the plane shown by the line 2—2 in FIG. 6.

FIG. 3 is a view similar to FIG. 1 showing the relationship between the flywheel magnet and the armature at starting speeds.

FIG. 4 is a view similar to FIG. 2 showing the relation between the breaker cam and cam follower at starting speeds, portions of the cam being broken away to the level of the notches provided in its lower margin.

FIG. 5 is a graph in which spark coil output is plotted against shaft r.p.m.

FIG. 6 is a diagrammatic view of the shaft and cam and operating weight in side elevation.

FIG. 7 is a view similar to FIG. 6 showing the cam and weight and spring and guide pin in relatively separated positions in side elevation.

The shaft shown at 8 would normally be an extension of the engine crankshaft tapered at 9 to receive the magneto flywheel 10 in which there is incorporated a magnet 15 having polar shoes at 16 and 17. The designation of

the poles by reference characters N and S is arbitrary and merely by way of example.

In accordance with conventional practice, the polar shoes 16 and 17 have surfaces at 18 and 19 which are of uniform radius for rotation in immediate proximity to the three legs of the conventionally laminated (lamination not shown) three legged armature 20. As shown by the arrow 21 in FIG. 1 and FIG. 3, the assumed direction of rotation of the flywheel is clockwise. The surface 19 of the S pole 17 first comes into registry with the end leg 23 of armature 20, subsequently registering with the center leg 24 upon which the coils 25 are wound and finally coming into registry with the end leg 26. The primary and secondary are normally connected as diagrammatically shown in FIG. 1.

The first substantial buildup of flux in the E armature 20 occurs in the position of the parts shown in FIG. 1, the flux flowing from the N pole outwardly through the leg 23 of the armature and back through the center leg 24 to the S pole as indicated by the arrows 27 and 28 in FIG. 1.

During continued rotation of the flywheel 10, the surface 18 of the north polar shoe 16 then comes into registry with the center leg 24 while the surface 19 of the south polar shoe 17 comes into registry with the leg 26. As this occurs, there is a reversal of flux in the center leg 24 which threads the coils 25. In the FIG. 1 position of the parts, the flux threading the coil from north to south was passing inwardly through the center leg 24 as shown by the arrow 28. In the FIG. 3 position of the parts, the flux threading the center leg 24 through the coils 25 from north to south is passing outwardly through the coils as shown by the arrow 29 and is returned through leg 26 as shown by arrow 30.

The breaker is generally conventional, comprising a grounded contact 32 which, although mounted on the usual spring 33 is relatively fixed. Movable to and from the contact 32 is the movable contact 35 series connected with the primary coil and carried by spring 36, upon which is mounted the cam follower 37.

The cam 38 which operates the follower 37 to open and close the breaker contacts or points 32 and 35 is illustrated as a sleeve encircling the magneto shaft 8 and oscillatable with respect thereto. It is confined by a split ring 39. The camming surface comprises a "flat" 40 which is centrally reduced in radius sufficiently to permit the contacts to close as shown in FIG. 4. When the flat 40 is not in registry with the follower 37, the cam opens the coil circuit through contacts 32 and 35.

The cam may conveniently rest on a sheet metal slide 41 which carries the flyweight 42, the weight being almost wholly at one side of the axis of shaft 8. Both the sheet metal slide 41 and the flyweight 42 are cut away to encircle the shaft 8. An inwardly projecting lug of the flyweight at 43 engages in a radial notch or opening 44 in the cam sleeve 38 so that the transverse reciprocation of the cam sleeve in response to centrifugal action of the flyweight in one direction and the converse bias of the spring in the opposite direction will communicate rotative movement to the cam sleeve respecting shaft 8.

The flyweight is socketed at 44 to receive a pin 45 that extends diametrically through shaft 8 and serves as a guide for the compression spring 46. The reduced extremity 47 of the pin 45 is seated in a down turned lug 48 of the slide 41. The bias of spring 46 normally maintains the slide 41 and flyweight 42 in the retracted position shown in FIG. 4. At some given speed determined by design, and here exemplified by an assumed shaft speed of about 500 r.p.m., the flyweight and slide will move from the position of FIG. 4 to the position of FIG. 2 against the bias of spring 46, thereby compressing

the spring and rotatively advancing the cam sleeve 38 in the direction of shaft rotation to advance the spark. That is to say, the opening and closing of the contact points 32 and 35 will occur earlier in the rotation of the shaft at high speeds than at low speeds.

As the speed of shaft 8 decreases below the assumed rate of 500 r.p.m., the bias of spring 46 will overcome the centrifugal force of flyweight 42 to retract the slide to the position of FIG. 4, thereby retarding the spark. As a convenient means of defining the two positions of the cam sleeve 38 with respect to shaft 8, the cam sleeve may conveniently be provided with notches 450 and 451 on a diameter substantially at right angles to the notch 44. The notches 450 and 451 straddle the pin 45, the notch 450 also accommodating a compression spring 46 as shown in FIG. 4. In the retracted position of the cam shown in FIG. 4, the position thereof is defined by engagement of the pin with that portion of the cam which is at the left of notch 450 and at the right of notch 451. In the advanced position of FIG. 2, the pin 45 and spring 46 are engaged by portions of the cam which are at the left of notch 451 and at the right of notch 450.

In the FIG. 5 graph, the curve 43 shows a typical relationship between the kv. output of the magneto with an open circuit in a conventional magneto having no spark advance. The curve generically designated by reference character 50 shows the kv. open circuit output of a magneto made in accordance with the present invention. It will be observed that whereas the standard magneto has an output of only about nine kv. at 100 r.p.m. (the assumed figure is arbitrary but fairly represents the situation), the magneto of the present invention under like conditions has an output of thirteen kv., or an increase of over forty percent.

The curve 50 shows that the magneto of the present invention not only maintains but actually increases its advantage over curve 43 at all speeds used in starting and in low speed operation. By the time the advance occurs at the assumed speed of 500 r.p.m., the kv. output is ample, even though the breaker is now operating at a relatively lower peak in rate of change of the flux threading the coils. Because of this change in peak, there will be a sharp drop in the portion 51 of curve 50 but the kv. output will still be considerably in excess of that which was available for starting. During continued increase in r.p.m., the kv. output will continue to build up as shown by the portion 52 of curve 50.

It will, of course, be clear that the purpose in advancing the spark is to assure better combustion of the fuel at high speed. It is conventional in both four-cycle and two-cycle engines to advance the spark for high speed operation. However, the apparatus employed for a spark advance in conventional magnetos and other timers involves shifting of the position of the breaker points, an arrangement made unnecessary by the present device which takes advantage of the fact that a magneto has more than one peak at which breaker point operation either in a closing or an opening direction will assure adequate ignition current, particularly if the higher peak is used for starting and the relatively lower peak for high speed operation in accordance with the present disclosure.

In the specific embodiment disclosed, for the purposes of exemplifying the invention, the cam has an oscillatory movement of approximately nineteen degrees with reference to the magneto shaft to effect an advance of the spark from approximately eleven degrees before top dead center to approximately thirty degrees before top dead center, this advance being achieved with simpler and less expensive moving parts than are normally required for ignition spark advance and retard.

In the low speed operation the breaker interrupts the primary circuit at the time of reversal of flux threading the coil in the center leg of the laminated armature 29; in high speed operation, the breaker opens the primary circuit at the time of flux introduction into the center leg and the coil.

I claim:

1. In a magneto having a coil and means including relatively movable magnet and armature parts for developing flux change in said coil at a plurality of points in the course of such movement, the combination with a breaker including a shaft, contact points having a cam follower for their operation, and a cam on the shaft, of means for automatically shifting in a direction angularly of the shaft the point of cooperative actuation of the cam follower by the cam from a first position in which flux change is developed in said coil to a second position in which flux change is developed in said coil, said shifting means comprising an off center weight provided with a slide guiding it for movement diametrically of the shaft, the shaft having a transverse bore, a pin extending through the bore and seated in the weight at one end and having a connection with the slide at its opposite end, said weight having a motion transmitting connection to the cam and the cam being mounted rotatably on the shaft for movement with respect to the shaft in the course of its rotation with the shaft, and a spring biasing said weight toward the shaft axis, spring encircling the pin and having seats on the shaft and the slide.
2. In a magneto, the combination of a shaft, a magnet carried thereby and provided with polar shoes angularly spaced in the direction of shaft rotation, a three-legged armature having its legs spaced proximate the path of shoe rotation and provided with coil means wound upon its center leg to be threaded by flux developed in the armature and having rate of flux change peaks at a plurality of points as said polar shoes rotate past the legs of the armature, a breaker connected in series with the coil means, said breaker including relatively separable contact points, and means for actuating said points for separation with respect to each other including means for automatically shifting with respect to said shaft the timing of actuation of said points from registry with one of said peaks to registry with another thereof.
3. In a magneto, the combination with a shaft and a magnet carried thereby and provided with polar shoes angularly spaced in the direction of shaft rotation, of a three-legged armature having its legs spaced proximate the path of shoe rotation and provided with coil means wound upon its center leg to be threaded by flux developed in the armature and having rate of flux change peaks at a plurality of points as said polar shoes rotate past the legs of the armature, a breaker connected in series with the coil means and including relatively separable contact points, and means for actuating said points for separation with respect to each other including a cam mounted on the shaft for angular oscillation relative thereto, a cam follower connected with one of the breaker points and with which the cam interacts, and means for automatically shifting with respect to said shaft the timing of actuation of said points for registry with one of the said peaks to registry with another thereof, said shifting means comprising a weight having its net mass off center respecting the shaft and provided with means biasing it toward the shaft, means guiding said weight for centrifugally operable movement of its net mass away from the shaft in opposition to said bias at a predetermined shaft speed, said guiding means comprising a slide upon which said weight is mounted for movement diametrically of the shaft, the weight and cam respectively having interengaged motion transmitting parts, and means on the shaft for directing said slide movement, whereby movement of the weight and slide effects cam oscillation respecting the shaft for a distance angularly equivalent to the distance of shaft rotation between the points at which said peaks occur, the means directing the slide comprising a pin extending through a bore with which the shaft is provided, the pin being connected at its ends with the slide, said biasing means comprising a spring encircling the pin and having a seat at one end against the shaft and a seat at its other end against the slide.
4. The device of claim 3 in which the interengaging

parts of the weight and the cam comprise a finger on the weight, the cam having a notch in which the finger is engaged.

5. The device of claim 3 in which the cam has notched portions straddling the pin and comprising surfaces spaced at said notched portions sufficiently widely to accommodate oscillatory movement of the cam respecting the pin and to define the extent of such movement.

6. In a magneto, the combination of a rotatable shaft, an E-shaped armature including a pair of end legs and a center leg, and coil means wound on the center leg of said armature, a sole magnet carried by said shaft for travel relative to said armature in response to rotation of said shaft, said travel of said magnet relative to said armature producing a first peak condition of substantial flux change in said armature incident to registry of said magnet with the central leg and one of said pair of end legs, and a second peak condition of substantial flux change in said armature incident to registry of said magnet with said center leg and the other of said pair of end legs, a cam carried by said shaft for rotation by said shaft and for oscillation relative to said shaft, a breaker including separable points, said points being operated by action of said cam in response to rotation of said shaft, and means for effecting oscillation of said cam relative to said shaft between first and second cam positions respectively operable to open said points during said first and second peak conditions of substantial flux change.

7. A magneto in accordance with claim 6 wherein one of said flux change conditions is of greater magnitude than the other and occurs when said magnet is in angularly spaced relation in the direction of rotation of said shaft from its position during the condition of lesser flux change, and

said means for effecting oscillation of said cam is operable to effect opening of said points during the occurrence of said greater flux change condition when said shaft is rotating at relatively low speeds and is operable to effect opening of said points during the occurrence of said lesser flux change condition when said shaft is rotating at relatively high speeds.

8. In a magneto, means including relatively movable magnet and armature parts for developing at least two peak conditions of rate of flux change in response to relative rotation between said magnet and said armature parts, an ignition circuit including a spark plug, and means for selectively operating said ignition circuit to produce a spark at said plug at times corresponding to the occurrence of said peak conditions of rate of flux change.

9. In a magneto, the combination of a shaft, a magnet carried thereby and provided with polar shoes angularly spaced in the direction of shaft rotation, a three-legged armature having two legs spaced proximate to the path of shoe rotation and provided with coil means wound upon its center leg to be threaded by flux developed in the armature and having rate of flux change peaks at a plurality of points as said polar shoes rotate past the legs of said armature, a breaker connected in series with said coil means, said breaker including relatively separable contact points and means for actuating said points for operation with respect to each other including a cam on said shaft mounted for angular oscillation with respect to said shaft, a cam follower connected with one of said breaker points and with which said cam interacts, and means for automatically shifting with respect to said shaft the timing of actuation of said points from registry with one of said peaks to registry with another of said peaks, said shifting means comprising a weight having its net mass off center with respect to said shaft and provided with means biasing it toward said shaft, means guiding said weight for centrifugally operative movement of its

net mass away from said shaft in opposition to said bias at a predetermined shaft speed, said guiding means comprising a slide upon which said weight is mounted for movement diametrically of said shaft, said shaft having means for directing said slide movement, and a motion transmitting connection with said weight for effecting angular cam displacement with respect to said shaft for a distance angularly equivalent to the distance of shaft rotation between the points at which said peaks occur, said motion transmitting connection including interengaged parts whereby the movement of said weight with said slide effects cam oscillation with respect to said shaft.

10. An ignition device including a sole magnet having a pair of pole faces of opposite polarity, an armature including, in series, first, second, and third legs and a primary winding on said second leg, means mounting said magnet and said armature for relative rotative movement therebetween, circuit breaker means connected to said primary winding, and means for selectively operating said circuit breaker means for production of a spark by a spark plug when said magnet is in a first position inducing flux along a path through said first and second legs and when said magnet is in a second position inducing flux along a path through said second and third legs.

11. An ignition device including a sole magnet having a pair of pole faces of opposite polarity, an armature including, in series, first, second, and third legs and a primary winding on said second leg, means mounting said magnet and said armature for relative rotative movement therebetween to establish first and second successively occurring flux paths in said second leg and to successively induce flux flow along said first and second paths, said first flux path extending in said first and second legs and said second flux path extending in said second and third legs, circuit breaker means connected to said primary winding, and means for selectively operating said circuit breaker means for production of a spark by a spark plug when said magnet is in a first position inducing flux flow along said first path and when said magnet is in a second position inducing flux flow along said second path.

12. An ignition device including a sole magnet having a pair of pole faces of opposite polarity, an armature including, in series, first, second, and third legs and a primary winding on said second leg, means mounting said magnet and said armature for relative rotative movement therebetween for successively inducing flux in said second leg along successively occurring first and second paths, said first path including said first and second legs and generally excluding said third leg, and said second path including said second and third legs and generally excluding said first leg, circuit breaker means connected to said primary winding, and means for selectively operating said circuit breaker means for production of a spark by a spark plug when said magnet is in a first position inducing flux flow along said first path and when said magnet is in a second position inducing flux flow along said second path.
